UNITED STATES PATENT OFFICE.

ALFRED RUSBATCH, OF CLEVELAND, OHIO.

WIRE-DRAWING MACHINE.

No. 900,816

Specification of Letters Patent.

Patented Oct. 6, 1908.

Application filed January 11, 1904. Serial No. 188,466.

To all whom it may concern:

Be it known that I, ALFRED RUSBATCH, a citizen of the United States, resident of Cleveland, county of Cuyahoga, and State of Ohio, have invented a new and useful Improvement in Wire-Drawing Machines, of which the following is a specification, the principle of the invention being herein explained and the best mode in which I have 10 contemplated applying that principle, so as to distinguish it from other inventions.

My invention relates to mechanism for drawing wire and particularly to that class of such mechanism in which the wire is drawn 15 successively through a plurality of dies, and generally known as "continuous wire-drawing machines." The object of said invention is to effect the drawing of wire in an economical and efficient manner.

20 The invention consists of means hereinafter fully described and particularly pointed out in the claims.

The annexed drawings and the following description set forth in detail certain mechanism embodying the invention, such disclosed means constituting but one of various mechanical forms in which the principle of the invention may be used.

In said annexed drawings:—Figure 1 represents a side elevation of a machine embodying my invention, showing the frame and dies in vertical longitudinal section. Fig. 2 represents a plan of such machine as viewed from above, the upper movable compensating guide pulleys shown in Fig. 1 being omitted. Fig. 3 represents an end elevation of same. Figs. 4 and 5 represent, on an enlarged scale, axial and transverse sections respectively of one of the drawing blocks embodied in said 40 machine.

Upon the lower part of a suitable frame A, are mounted a plurality of parallel driving spindles B and upon one end of each is mounted a beveled gear b, such gears varying 45 in size from a maximum at the front end (right hand as viewed in Fig. 2) to a minimum at the opposite or rear end. A longitudinal main driving-shaft C is provided with a plurality of beveled gears c respectively engaging the gears b as shown in Fig. 2. Each spindle B forms the lower spindle of a speed changing device D whose upper spindle B' is mounted on the upper part of said frame A, as shown in Fig. 3. The construction of each 55 of these speed changing devices may be that

of any one of various well-known mechanisms used for this purpose, the form shown in said figure being one frequently used for effecting various changes of speed, and since it *per se* does not form a part of my invention it need not be herein described in detail. It is sufficient to merely explain that each such device is provided with a hand-wheel D' by means of which the diameters of upper and lower pulleys d and d' mounted upon spindles B and B', are respectively increased and diminished simultaneously so as to vary the speed of the upper spindles B', as required. Upon one end of each spindle B' is mounted a cylindrical wire drawing block E. 70 Each such block is formed with two slots e parallel with its axis and intersecting its spindle bore, as shown in Figs. 4 and 5.

The surface of one side of each slot is substantially radial with respect to the block and the other side curved as shown. Two spring-actuated pawls e' e' normally engage these slots respectively, and are provided with straight and curved sides as shown, the arrangement being such that the driving spindle engages and fixes the block relatively to itself, when rotated in the direction required to draw the wire from front to rear of the machine, but may be caused to disengage same when rotated in the opposite direction. 85 Such construction allows the block to be rotated in the normal direction of rotation at a speed greater than and prohibits its rotation at a less rate of speed in such direction than that of its spindle, and also allows the blocks to be rotated in said direction when the spindles are idle. The utility of such arrangement will hereinafter appear.

In front of each block is mounted a die F, the diameter of the die openings varying from the maximum at the front to a minimum at the rear of the machine, as is usual in this class of devices. Intermediately of each block and the succeeding die is located a guiding pulley G which guides the wire into such succeeding die and is mounted upon the frame of the machine.

Above the frame and hung from a suitable support H is a series of pulleys H' H'', etc., corresponding in number with the number of spaces intermediate of the blocks and dies and having their axes located in a vertical plane passing through such spaces. Each such pulley is supported by a rope or chain h which runs over a pulley h' fixed to said sup-

port. This rope passes laterally over a pulley h^2 fixed to a support H^2 , and to its free end is secured a suitable weight h^3 .

The rearmost block E is of longitudinally enlarged form such as is usually provided for winding or reeling up the wire.

In preparing for the operation of the above described mechanism, the wire is passed through the first die, then given several turns 10 around the first block. It is then passed upwardly and over the first pulley H' , then downwardly around first pulley and through the second die. In so passing the wire, the latter is fore-shortened sufficiently to pull 15 the pulley downwardly some distance so as to yield and cause the weight h^3 to tend to move same away from the block and to exert a pull upon the loop k of the wire, and the pulley to constantly tend to retract and 20 maintain a substantially constant tension in the wire of such loop. A similar process of stringing the wire is followed with respect to the succeeding blocks, pulleys and dies. Each pulley H' hence forms a yielding re- 25 tractile means for guiding and supporting the wire intermediate of its respective block and guiding pulley G. The blocks are rotated at speeds varying from a minimum at the front to the maximum at the rear of the 30 machine as previously described, so as to draw the wire without buckling. After the machine has been properly adjusted to effect the drawing as required, the operation continues as described until one of the dies wears 35 to a larger diameter. When a certain degree of enlargement is effected in any one die, the loop succeeding such die becomes elongated above the normal. This is brought about by reason of the fact that more than the normal 40 amount of stock is fed to the succeeding die and part of the drawing operation which should have been performed by the enlarged die is performed by the said succeeding die. This elongation is, however, taken up by the 45 action of the weight upon the corresponding pulley, so that the required tension upon the loop is maintained and the defect of the die is indicated by the upward movement of the

pulley. In order then to prevent a continuation of such elongation from effecting the 50 buckling of the wire, it is only necessary to speed up the blocks succeeding the defective die, in progressively varying degrees, by means of the change-speed mechanism.

Such described effect upon the operation of 55 the die succeeding the defective die is also accompanied by a foreshortening of the loop of wire preceding such defective die for the reason that since more stock is passed through said die, a greater length is drawn 60 through same in a given time. In the event that no means were provided to compensate for such increase of speed, the wire preceding such die would be stretched and unevenly elongated, such action having been found to 65 impart an oval or elliptical cross-section to such wire. Such action is, however, prevented by the yielding of the corresponding pulley H' , until the mechanism is again readjusted to correct the variation. 70

Other modes of applying the principle of my invention may be employed instead of the one explained, change being made as regards the mechanism herein disclosed provided the means stated by the following claim or the 75 equivalent of such stated means be employed.

I therefore particularly point out and distinctly claim as my invention—

In a wire drawing machine, the combination of a die, a drawing drum therefor, a second die adapted to operate upon the wire after it has passed through the first mentioned die, a second drawing drum therefor, common operative means for both said drums, said means including a ratchet device 80 adapted to drive the first mentioned drum at its minimum rate of speed, but so constructed as to permit of free forward rotary movement of said drum at a greater speed. 85

Signed by me, this 6th day of January, 90 1904.

ALFRED RUSBATCH.
